UNITED STATES PATENT OFFICE.

WILLIAM D. BRUNDAGE, OF ALBION, MICHIGAN.

SPRING FOR CULTIVATOR-BEAMS.

SPECIFICATION forming part of Letters Patent No. 596,038, dated December 21, 1897.

Application filed July 3, 1896. Serial No. 597,996. (No model.)

To all whom it may concern:

Be it known that I, WILLIAM D. BRUNDAGE, a citizen of the United States, residing at Albion, in the county of Calhoun and State of Michigan, have invented certain new and useful Improvements in Springs for Cultivator-Beams; and I do hereby declare the following to be a full, clear, and exact description of the invention, such as will enable others skilled in the art to which it appertains to make and use the same.

My invention relates to the class of cultivators, and more particularly to the class of wheel-cultivators which are termed "straddle-row" cultivators, or those having two beams each carrying cultivator-blades for working on each side of a row of plants. In such cultivators heretofore springs have been employed that at all times exert a lifting action upon the beams and cultivators, and also springs that at all times exert their force to depress the beams and cultivators, and, further, springs that exert their power both to lift and depress the beam, said springs acting when the beam is forced below a certain median line to depress the beam and cultivators and acting when the beam is raised above the said line to lift the cultivators and hold the beam and cultivators in an elevated position.

My invention consists in an improved construction of spring and its connections with the beam and frame whereby the said spring within certain limits practically serves as a counterbalance for the beam and cultivator-blades, so that when the beam is in the operative position, or the position in which it is when the cultivator is doing work, the beam and its attached cultivator-blades will be balanced and will remain in that position unless moved therefrom by some exterior force or power, and when raised to any point within easy movement by the hand of the operator the beam will still be balanced by the spring and will remain in the position in which it is brought unless forced therefrom.

In the accompanying drawings I have illustrated one form in which I have contemplated embodying my invention, and said invention is disclosed in the description and claims of this application.

In the drawings, Figure 1 is an isometric

view of the frame of a cultivator with my improved spring attached thereto. Fig. 2 is an enlarged side view. Fig. 3 is a still further enlarged detail of construction, and Fig. 4 shows a modification.

In the figures, A is the arched axle or frame, and B is the plow or cultivator beam, to which is attached one or more plows or cultivator-blades. This beam is secured in any preferred manner to a sleeve C, loosely mounted on a horizontal part of the axle near the supporting-wheels. This beam is secured to the sleeve so as to be free to be moved laterally while the sleeve, turning freely upon the axle, permits vertical movement. The sleeve C is provided with arms *cc'*, extending on opposite sides thereof and rigid therewith. These arms may be secured to the sleeve or made integral therewith, as may be found most convenient. Near the upper end of one of the vertical portions of the arch is pivoted a lever D, to the forward end of which is secured one end of the spring E. The opposite end of the spring is secured to the rearwardly-extending arm *c*, secured to the sleeve C. To the rearward end of the lever D is pivoted one end of a link F, which extends downwardly and forwardly and is pivoted to the arm *c'* of the sleeve C. The link F is bent, as shown, so that the central portion thereof lies in a different plane from its ends, so as to enable the link to cross the spring E without coming in contact therewith.

By preference the spring E is connected at one end, so that adjustment can be made to increase or decrease the tension of the spring. In this instance the spring E is connected to a bolt *e*, which passes through the lever D, and is secured by a nut which can be turned to effect the desired adjustment of the spring.

In Figs. 1 and 2 I have shown an extension-spring, but a compression-spring can be employed instead, as shown in Fig. 4. In this figure the spring E' has its lower end bearing against a plate G, which is supported by two rods *g g*, connecting it to the lever D', which is a slightly-modified form of the lever D in the other figures. The beam is connected with the spring by a link and a rod *b*, passing through an opening in the plate G and through the interior of the spring. This rod has a collar *b'* at its upper end bearing on the top

of the spring. The link F and the other parts may be of the same construction as in the other figures.

The beam requires the greatest force to sustain it when it is in the horizontal position; but a spring adjusted to exactly balance a beam in that position would not hold it when raised above it, as the force of the spring would be diminished. In order to enable the beam and plows to be held or balanced, means must be provided to apply a certain amount of tension to the spring as the beam is raised; but as the force required to balance the beam and hold it lessens as the beam is raised the tension applied on raising the beam must not be such as to cause the spring to exert the same force as when the beam is in a horizontal position. When the spring has been given a tension just sufficient to balance the beam, it is only necessary to fix the pivotal point of the lever D so as to secure the desired increment of tension in raising the beam. This mode of balancing the beam is found to reduce the labor of the operator to the minimum. But little more force is required to raise or depress the beam than to raise or lower the hand.

What I claim, and desire to secure by Letters Patent, is—

1. A wheel-cultivator having a plow or cultivator beam pivoted to move up and down vertically, a spring-balance for holding it in position when lifted or depressed to any point within a certain range of its movement, substantially as described.

2. A wheel-cultivator having a main frame, a plow or cultivator beam pivoted to the main frame to permit said beam to move up and down vertically, a spring and adjusting mechanism therefor balancing said beam to hold it in position when moved to any point within

a certain range of its vertical movement, substantially as described.

3. In a wheel-cultivator, the combination with the main frame, of a pivoted plow or 45 cultivator beam, and a spring and lever interposed between said beam and the main frame and holding the said beam balanced at any point within a certain range of movement, substantially as described. 50

4. In a wheel-cultivator, the combination with the main frame, of a pivoted plow or cultivator beam, and a spring and lever interposed between said beam and main frame and adjusting means for said spring and lever for holding the said beam balanced in its 55 operative position, substantially as described.

5. A wheel-cultivator having a main frame, a pivoted plow or cultivator beam, a lever pivoted upon the said main frame, a spring 60 between said lever and plow-beam and adjusting mechanism for said spring connected with said lever, whereby the said beam is balanced when brought to different positions in its range of movement, substantially as 65 described.

6. In a cultivator the combination with the main frame and pivoted plow-beam, of a lever pivoted to the main frame, arms connected for vertical movement with said plow-beam 70 and extending on each side of its pivot, a spring connecting the rearwardly-extending arm with the forward end of said lever, and a link connecting the forwardly-extending arm with the rearward end of said lever, sub- 75 stantially as described.

In testimony whereof I affix my signature in presence of two witnesses.

WILLIAM D. BRUNDAGE.
